MIXING VALVE

William H. Armstrong, Birmingham, Mich., assignor to
Borg-Warner Corporation, Chicago, Ill., a corporation
of Illinois

Filed July 30, 1963, Ser. No. 76,037

Term of patent 14 years

(Cl. D91—3)

FIG. 1 is a side elevation view of a mixing valve embodying my new design; and

FIG. 2 is a front elevation view thereof.

The top and bottom are flat and plain, and the side opposite that shown in FIG. 1 is a mirror image thereof.

I claim:

The ornamental design for a mixing valve, substantially as shown and described.
